(57) **CLAIM**

The ornamental design for a urine absorbing sheet for pets as shown and described.

DESCRIPTION

FIG. 1 is a front view of a urine absorbing sheet for pets showing my new design;

FIG. 2 is a rear view thereof;

FIG. 3 is a top plan view of the thereof;

FIG. 4 is a bottom plan view thereof;

FIG. 5 is a right side view thereof;

FIG. 6 is a left side view thereof;

FIG. 7 is a perspective view thereof;

FIG. 8 is an enlarged view of the portion indicated in FIG. 1;

FIG. 9 is an enlarged sectional view taken along the lines 9-9 of FIG. 8; and,

FIG. 10 is an enlarged sectional view taken along the lines 10-10 of FIG. 8;

The broken lines showing of the urine absorbing sheet for pets are included for the purpose of illustrating portions of the article and form no part of the claimed design.

The long-dash short-dash broken lines FIGS. 1 and 8 show the boundaries of the enlargement shown in FIG. 8 and form no part of the claimed design.

1 Claim, 10 Drawing Sheets
